UNITED STATES PATENT OFFICE.

IVAN CHANDLER DRESSER, OF YONKERS, NEW YORK.

DESIGN FOR A FARINACEOUS CUP.

Application filed December 19, 1923. Serial No. 8,093. Term of patent 14 years.

To all whom it may concern:

Be it known that I, IVAN CHANDLER DRESSER, a citizen of the United States, residing at Yonkers, county of Westchester, and State of New York, have invented a new, original, and ornamental Design for Farinaceous Cups, of which the following is a specification, reference being had to the accompanying drawing, forming part therof.

I claim:—

The ornamental design for a farinaceous cup, as shown.

IVAN CHANDLER DRESSER.
